CLAIM

The ornamental design for a pad for a lumbar spine coil for a magnetic resonance imaging device, as shown and described.

DESCRIPTION

FIG. 1 is a front, top and right side perspective view of a pad for a lumbar spine coil for a magnetic resonance imaging device showing our new design;

FIG. 2 is a top plan view thereof;

FIG. 3 is a right side elevational view thereof;

FIG. 4 is a front elevational view thereof;

FIG. 5 is a left side elevational view thereof;

FIG. 6 is a bottom plan view thereof;

FIG. 7 is a rear elevational view thereof; and,

FIG. 8 is a top, right side and front perspective view thereof, on a reduced scale, shown in use. The broken line showing of a table is for illustrative purposes only and forms no part of the claimed design.

The broken lines shown in FIGS. 1, 3, 4, 5, and 6, represent stitching.
